UNITED STATES PATENT OFFICE.

CHARLES E. BLUE, OF WHEELING, WEST VIRGINIA, ASSIGNOR TO DARWIN S. WOLCOTT, OF SEWICKLEY, PENNSYLVANIA.

MANUFACTURE OF GLASS.

13,723.

Specification of Reissued Letters Patent. Reissued May 12, 1914.

Original No. 1,015,538, dated January 23, 1912, Serial No. 452,193. Application for reissue filed November 8, 1913. Serial No. 800,009.

To all whom it may concern:

Be it known that I, CHARLES E. BLUE, of Wheeling, Ohio county, West Virginia, have invented a new and useful Improvement in the Manufacture of Glass, of which the following is a full, clear, and exact description, reference being had to the accompanying drawings, forming part of this specification, in which—

10 Figure 1 is a plan view, with a portion of a melting furnace or vessel in section, of one form of apparatus embodying my invention; Fig. 2 is a vertical section of the same; Fig. 3 is a broken sectional plan view showing 15 the discharge portion of the melting vessel or furnace; Fig. 4 is a view similar to Fig. 1, but showing a modification; Figs. 5 and 6 are sectional detail views of the measuring receptacles shown in Fig. 4, showing the 20 manner of discharging the same; Fig. 7 is a detail sectional view of the measuring receptacle illustrated in Figs. 1 and 2; Fig. 8 is a detail sectional view of another modification of measuring device; Fig. 9 is an 25 end view of the receptacle shown in Fig. 7; Fig. 10 is a detail view showing the manner in which the receptacle shown in Figs. 1, 2 and 7 are tipped into discharging position; Fig. 11 is a detail view of one set of 30 intermittently acting gears; and Figs. 12 and 13 are detail views showing the cam for closing the valves of the measuring receptacle shown in Figs. 4, 5 and 6. Fig. 35 14 is a detail sectional view of one of the measuring receptacles on a larger scale and showing a different form of receptacle; Fig. 15 is a detail plan view of the latch device; Fig. 16 is a detail view of the cam for re-closing the receptacles; Fig. 17 is a detail 40 view of the shear or cutoff device; and Fig. 18 is a detail view of a cam device for releasing the latch shown in Fig. 14.

My invention relates to the manufacture of glass, and is designed to provide novel means for transferring the glass from a melting vessel, without the necessity of gathering the glass in the manner commonly employed. In accordance with my invention, a stream of molten glass is caused 45 to flow continuously from the melting pot or vessel into a plurality of receptacles brought successively in position to receive the same, each of said receptacles being arranged to receive a suitable quantity of

glass. After each receptacle has been filled 55 in this manner, the glass in two adjacent receptacles is cut off or sheared, after the receptacle has been moved away from the continuously flowing stream, and the receptacles are then transferred to a discharging 60 station, where their contents are discharged into a mold vessel.

The precise nature of my invention will be best understood by reference to the accompanying drawings, which will now be 65 described, it being premised, however, that the invention is susceptible of various changes and modifications by those skilled in the art without departing from the spirit and scope as defined in the appended claims. 70

Referring first to the form of my invention which is shown in Figs. 1 and 2, the numeral 2 designates a melting pot or vessel, having an overhanging spout 3 through which a continuous stream of glass is caused 75 to flow while the machine is in operation. 4 designates a series of receptacles or cups, which are arranged to be brought successively into position to receive the glass discharged from the spout 3. Each of these 80 receptacles is mounted upon the outer-end portion of a radially extending arm 5. The series of arms 5, of which five are shown in the present instance, are connected at their inner ends to a sleeve 6 mounted 85 around a shaft 7. These sleeves 6 are mounted one around and upon another in the manner clearly shown in Fig. 2, the sleeves being of different lengths at both their upper and lower ends, and the arms 90 5 excepting the upper arm have bent portions 5^a which bring them from the plane of the upper end portion of their respective sleeves into the plane of the upper surface of the apparatus, the several cups 4 being 95 all in the same horizontal plane. On the lower end portion of each sleeve 6 is an interrupted pinion 8, which is arranged to be driven by a gear wheel 9 having intermittent teeth. one of these pinions and its 100 gear wheel being shown in detail in Fig. 11. As will be clearly understood from Fig. 2, each sleeve is provided with one of the pinions 8, placed one above another about the shaft 7, as an axis, and the gear wheels, 105 9 are similarly arranged upon a shaft 10 to which they are secured. The shafts 10 and 7 are also intergeared by means of the

spur gear wheels 11 and 12, so that the shaft 7 will be continuously rotated. The shaft 10 is rotated by a worm gear connection 10^a with a motor 10^b. On the upper end of the 5 shaft 7 is a beveled toothed wheel 13, whose teeth are engaged by a bevel pinion 14 on a radial shaft 15 mounted in bearings 16 of the frame 17, and carrying at its outer end a beveled toothed pinion 18. On each arm 10^c 5 is a toothed rack segment 19. These segments are so secured on the arms 5 as to be brought underneath the bevel pinion 18 and engage with the teeth thereof for the purpose hereinafter described. The cups or receptacles 4 are arranged to fit closely together in the manner shown in Fig. 1, with laterally extending cavities or depressions 4^a in their upper surfaces extending in both directions from their central receiving cavity, as clearly shown in this figure. The cups or receptacles are provided with the sleeves 20, which are revolvably mounted on the outer ends of the arms 5 in the manner clearly shown in Fig. 7, so that when 20 the cups are brought around to the discharging station they may be rotated in the manner hereinafter described into discharging 25 position, as shown in Fig. 10.

21 is a cam flange or projection which is 30 arranged to be engaged by a roller pin 22 on the sleeve 20 for the purpose of moving the cups in a radial direction toward the shaft 7, after they have been filled. The right-hand cup in Fig. 1 is shown as so 35 moved, this movement being for the purpose of shearing or cutting off the glass connecting the glass in two adjacent cups. The cam flange 21 also has an offset portion 21^a arranged to return the cups to their original 40 positions after the shearing has been effected.

The operation is as follows:—The intermittent pinions 8 and gears 9 are so timed and arranged as to successively move the 45 cups from the discharging station A to the receiving station B, at which they are filled. As each cup is brought adjacent to the charging station the portions 9^c and 8^c of its gear and pinion 8 and 9 pass out of 50 mesh and the plain untoothed portions 8^b and 9^b frictionally engage, and will herein-after shift the cup carrying arm until the cup bears against the preceding cup and the rack 19 on the arm 5 is engaged by the pinion 18, which positively shifts the cup into 55 receiving position under the spout 2, and from under said spout when filled. The movements of the cups from receiving position to a position where the toothed portions 9^a and 8^a of gears 9 and 8 will again engage, is effected in part by the frictional engagement of the parts 9^c and 8^c and in part by the push of the cup which has its 60 rack 19 in engagement with the bevel pinion 18. By employing a separate means for

moving the cup while it is being charged a slow motion can be given thereto, without interrupting or retarding the movements of other parts of the machine. After the shearing operation has been effected for each 70 cup, its intermittent gear and pinion actuating connections again come into action and the cup is moved rapidly around to the discharging station. The cup will be held in this position a predetermined time by the lock engagement between the portions 8^a and 9^a of the gears 8 and 9 respectively. For the purpose of tipping the cups at this 75 point to discharge their contents into a suitable mold vessel, each cup is provided with a projection, preferably in the form of a roller bearing 23, see Fig. 7, which comes into engagement with a cam member 24 in the manner shown in Figs. 1 and 10 thereby 80 rotating the sleeve 20 on the arm 5 and tipping the cup into the position shown in full in Fig. 10. The cam 24 has the inclined portion *a*, which effects the tipping, the raised straight portion *b* which holds the cup temporarily in tipped position and an 85 outwardly inclined portion *c* which returns the cup to its normal position.

25 designates a suitable carrier, having mounted thereon a series of mold vessels 26, which are designed to be brought successively into position to receive the contents of one of the cups 4 at the discharging station. As shown in Fig. 1, these mold vessels are capable of radial movement into and out of position to a point indicated at A to come 90 underneath one of the cups 4, but this part of the apparatus has nothing to do with my present invention, as any suitable means may be employed for bringing the mold vessels into position.

27 in Figs. 2 and 3 designates gas jets, which may be employed to maintain the 100 glass in the discharging spout 3 in a suitable fluid condition.

28 designates a gate or shutter by which 110 the flow of glass from the melting tank or vessel can be controlled at will or shut off entirely through any suitable actuating connections, such as those indicated at 29, controlled by the lever 30 (see Fig. 2).

The form of my invention shown in Fig. 4 is similar to that shown in Figs. 1 and 2, except that instead of employing a radial movement of the cups relatively to each other for the purpose of shearing or cutting 120 off the connecting portions of the glass, I provide adjacent to the charging station an overhanging scraper or shearing arm 31 (see Fig. 6), which as the receptacles are carried thereunder will scrape or sever such connecting portions. In this figure, I have also shown the cups as fixedly secured to their carrying arms 5^a instead of rotatably mounted thereon. For this purpose I provide the cups with hinged bottom closures 125 130

or valves 32, as best shown in Figs. 5, 6 and 8, these being normally held in closed position by the sliding spring latches 33. For the purpose of withdrawing these latches at the discharging station, to permit the bottom closures or valves 32 to open (as shown in Fig. 5) I provide the cam member 34 arranged to be engaged by a slot or fork 35 on the latch to cause the retraction of the latch. After passing the discharging station, these bottom valves may be closed by causing them to engage with the cam 36. A detail view of the cam member 24 is shown in Fig. 13. Detail views of the cam member 36 are shown in Figs. 12 and 16.

The advantage of my invention will be apparent to those skilled in the art, since it provides mechanism of simple character whereby measured quantities of glass may be delivered to the mold vessel without the gathering operation usually employed. It will be seen that in the apparatus shown the cups or receptacles are given a comparatively rapid motion from the discharging station around to the charging station; they are then moved slowly past the charging, settling and shearing stations; and are then again moved more rapidly around to the discharging station, where they are again held stationary for a short period by the interrupted gears. Any sufficient number of these receptacles may be employed, so that the stream of glass may flow continuously, with a receptacle at all times in position to receive such stream except during the short interval when one receptacle is being moved out of receiving position and another into receiving position.

The cup or receptacles 4, which are preferably constructed to serve as measures, may be of various forms. Thus, in Figs. 7 and 8, I have shown them as having a continuous inward contraction toward their discharge ends, while in Fig. 14 I have shown them as having the upper portion 4^b of the cavity contracted downwardly and joining a lower portion 4^c, which is of downwardly increasing diameter.

It will also be understood that various other changes may be made in the details of construction and operation. Thus, the means employed for bringing the cups or receptacles to the charging station and for moving them to the discharging station may be varied, together with the gearing employed; the receptacles may themselves be mounted in other ways, and may be discharged in any suitable manner.

I claim:—

1. In apparatus for the manufacture of glass, means for delivering a continuous stream of molten glass, a plurality of supports mounted for separate movement around a common center, and measuring cups or vessels mounted on the supports and

arranged to be moved thereby successively into position to receive the glass; substantially as described.

2. In apparatus for the manufacture of glass, means for delivering a continuous stream of molten glass, a plurality of supports mounted for separate movement around a common center, measuring cups or vessels mounted on the supports and arranged to be moved thereby successively into position to receive the glass, together with means for shearing or cutting off the glass between the receptacles on adjacent supports after they have been filled; substantially as described.

3. In apparatus for the manufacture of glass, means for delivering a continuous stream of molten glass, a plurality of supports mounted for separate movement around a common center, measuring cups or vessels mounted on the supports, and arranged to be moved thereby successively into position to receive the glass, and means for imparting independent movements to the supports around their common center; substantially as described.

4. In apparatus for the manufacture of glass, means for delivering a continuous stream of molten glass, a plurality of supports mounted for separate movement around a common center, measuring cups or vessels mounted on the supports and arranged to be moved thereby successively into position to receive the glass, and means for separately actuating said supports at different portions of their movements around their common center; substantially as described.

5. In apparatus for the manufacture of glass, means for delivering a continuous stream of molten glass, a plurality of supports mounted for separate movement around a common center, a measuring cup or vessel mounted on each of the supports, means for actuating the supports independently to bring the cups or receptacles successively in position to receive the molten glass, and means for shearing or cutting off the glass between adjacent cups or receptacles after they have been filled; substantially as described.

6. In apparatus for the manufacture of glass, a plurality of supports mounted for separate movement around a common center in a horizontal plane, a measuring cup or receptacle mounted on each support, means for separately actuating the supports, and means whereby the supports are actuated at different speeds during different portions of their rotary movement around their common center; substantially as described.

7. In apparatus for the manufacture of glass, a charging station having means for delivering a continuous stream of molten glass, a settling station, a shearing station.

- a discharging station, a plurality of measuring cups or vessels, a separately movable carrier for each cup or vessel mounted for separate movement around a common center, 5 together with means for actuating the same; substantially as described.
8. In apparatus for the manufacture of glass, a charging station having means for delivering a continuous stream of molten glass, a settling station, a shearing station, 10 a discharging station, a plurality of measuring cups or vessels, a separately movable carrier for each cup or vessel mounted for separate movement around a common center, 15 together with means for actuating the same, and actuating means being arranged to impart a different speed of movement to the supports at different portions of their movements; substantially as described.
- 20 9. In apparatus for the manufacture of glass, a plurality of rotary supports, separate gearing for rotating each support, and a measuring cup or receptacle mounted on each support, and means for imparting a 25 radial movement to each cup or receptacle relative to an adjacent receptacle at a given point in its movement; substantially as described.
10. Apparatus for the manufacture of 30 glass, having a plurality of radially arranged separately movable supports, separate gearing for actuating each of the supports, a measuring cup or vessel mounted on each support, and means for imparting a 35 shearing movement to each cup or vessel relatively to an adjacent vessel; substantially as described.
11. In apparatus for the manufacture of 40 glass, a supporting arm arranged to rotate in a horizontal plane, a measuring cup or receptacle mounted on said arm, and means for imparting a radial movement to said receptacle at a certain point during its rotary movement to shear the glass; substantially 45 as described.
12. In apparatus for the manufacture of 50 glass, a plurality of supporting arms mounted for separate movement around a common center in a horizontal plane, means for rotating said arms, a measuring cup or receptacle mounted on said arms and means for tipping the cups or receptacles at a point 55 in the movement of said arms; substantially as described.
- 60 13. In apparatus for the manufacture of glass, a supporting arm, gearing for rotating said arm in a horizontal plane at a pre-determined speed, and a second gear for imparting a different speed of movement to 65 said arm in different portions of its travel, and a measuring cup or vessel carried by said arms; substantially as described.
14. In apparatus for the manufacture of 70 glass, a supporting arm, gearing for rotating said arm in a horizontal plane and for im- parting a different speed of movement to 75 said arm in different portions of its travel, a measuring cup or vessel carried by said arm, and means for discharging the contents of said cup or receptacle; substantially as 80 described.
15. In apparatus for the manufacture of 85 glass, a plurality of supporting arms mounted for separate movement around a common center in a horizontal plane, measuring cups or receptacles mounted on said arms, and cam means for effecting the discharge of the contents of the cups or receptacles at a point in the movement of the arms about their common center; substantially as 90 described.
16. In apparatus for the manufacture of 95 glass, a supporting arm, gearing for rotating said arm in a horizontal plane, a measuring cup or receptacle mounted on said arm, and cam means for effecting a radial movement of the cup or receptacle to shear the glass; substantially as described.
17. Apparatus for the manufacture of 100 glass, comprising a plurality of supporting arms, means for rotating said arms in a horizontal plane, and a measuring cup or vessel mounted on each arm, said cups or vessels having lateral recesses or depressions at their upper portions at each side of their main cavity, together with means for shearing or cutting off the glass between adjacent cups or receptacles; substantially as 105 described.
18. In apparatus for the manufacture of 110 glass, a plurality of supporting arms mounted for separate movement around a common center in a horizontal plane, gearing for rotating said arms, measuring cups or receptacles loosely mounted on the arms and cam means arranged to engage the cups or receptacles to effect a tipping discharging movement thereof during the horizontal movement of the arms; substantially as described.
19. In apparatus for the manufacture of 115 glass, a plurality of separate supporting arms mounted for separate movement around a common center, a measuring cup or receptacle mounted on each arm, and intermittently acting gearing for imparting 120 separate movements to each arm; substantially as described.
20. In apparatus for the manufacture of 125 glass, a plurality of separate supporting arms, a measuring cup or receptacle mounted on each arm, intermittently acting gearing for imparting separate movements to each arm, and supplemental gearing for imparting a slow movement to the arms during one of the intervals when the intermittent gearing for that arm is not acting; substantially as described.
21. In apparatus for the manufacture of 130 glass, means for delivering a continuous stream of molten glass, a plurality of radi-

ally disposed supports mounted for separate movement around a common center, measuring cups or vessels mounted on supports and arranged to be moved thereby successively into position to receive the glass, together with means for moving said cups radially for shearing or cutting off the glass between the cups on adjacent supports after they have been filled; substantially as described.

22. In apparatus for the manufacture of glass, means for delivering a continuous stream of molten glass, a plurality of supports mounted for separate movement around a common center, measuring cups or vessels mounted on the supports and arranged to be moved thereby successively into position to receive the glass, means for imparting independent movements to the supports around their common axis, and means for imparting an independent radial movement to each of the cups or vessels to shear the glass between said adjacent cups or vessels; substantially as described.

23. In an apparatus for the manufacture of glassware, the combination of a plurality of cups or receptacles movable in a circuit, means for moving said cups independent one of the other in said circuit, means for delivering a continuous stream of glass arranged to charge said cups at a point in said circuit, and means for discharging the cups at another point in the circuit.

24. In an apparatus for the manufacture of glassware, the combination of means for delivering a continuous stream of molten glass, a plurality of cups or receptacles movable in a circuit, means for moving the cups along the circuit independent one of the other to bring them successively into position to receive the glass, and means for shearing the strand of glass extending from the charged cup.

25. In an apparatus for the manufacture of glass, means for delivering a continuous stream of molten glass, a plurality of cups or receptacles independently movable in a circuit relative to the stream of glass, and means for moving said cups at different speeds along said circuit.

26. In an apparatus for the manufacture

of glassware, the combination of means for delivering a continuous stream of molten glass, a plurality of cups or receptacles movable in a circuit past the point of delivery of the molten glass, means for moving the cups successively in the circuit to and from receiving position each being moved independently of the others, and means for discharging the glass from the cups.

27. In an apparatus for the manufacture of glass, means for delivering a continuous stream of molten glass, a plurality of cups or receptacles movable in a circuit, and means for imparting independent and intermittent movements to said cups along said circuit.

28. In an apparatus for the manufacture of glass, the combination of means for delivering a continuous stream of molten glass, receiving vessels, means for moving said vessels in succession to position to receive the glass, means for moving each vessel into close proximity to the vessel in receiving position, and means for segregating the glass in the charged vessel.

29. In an apparatus for the manufacture of glass, the combination of means for delivering a continuous stream of molten glass, receiving vessels, means for moving said vessels independently one of the other to position to receive the glass, means for simultaneously moving a charged vessel from charging position, and means for segregating the glass in the charged vessel.

30. In an apparatus for the manufacture of glass, the combination of means for delivering a continuous stream of molten glass, receiving vessels, means for moving said vessels successively and independently one of the other to position to receive the glass, means for simultaneously moving a charged vessel from charging position, means for segregating the glass in the charged vessel, and means for moving the charged vessel to discharging position.

In testimony whereof, I have hereunto set my hand.

CHARLES E. BLUE.
